COMBINATION SAFETY OIL GAUGE AND
LIGHT SWITCH

Charles Jeilik, Jr., St. Louis, Mo.

Application May 24, 1934, Serial No. 727,347

8 Claims. (Cl. 123—146.5)

My invention relates generally to instruments aiding in the efficient and safe operation and maintenance of internal combustion engines, particularly internal combustion engines of the stationary type which are kept running for long periods of time, and an important object of my invention is to provide fool-proof means for grounding out the ignition circuit of the engine upon a failure of the lubrication system of the engine, so as to stop the engine and thereby prevent damage to the engine from lack of oil.

It is also an important object of my invention to provide in an arrangement of the character indicated, especially adapted to installation on a motor vehicle, means for visibly indicating a condition of failure of the lubricating system, and control means for the ignition system, grouped with and combined with means for controlling the lighting system of the vehicle, whereby the utmost convenience and safety in the operation and control of these elements is procured.

Other objects and advantages of my invention will be apparent from a reading of the following description in connection with the drawings, wherein for purposes of illustration I have shown a preferred embodiment of my invention.

In the drawings:—

Figure 1 is an elevational view of the front of an embodiment of the invention.

30 Figure 2 is an elevational view of the back of Figure 1.

Figure 3 is an elevational view of the front of the dielectric panel.

Figure 4 is a longitudinal sectional elevational view of the bright-dim switch arm.

Figure 5 is an elevational view of the back of the switch mechanism showing the positions of the parts while the key is in the "off" position.

Figure 6 is a vertical transverse sectional view through the right hand side of Figure 5 disclosing the position of the parts of the switch mechanism while the key is in the "off" position.

Figure 7 is a transverse vertical sectional view through the oil gauge portion of the device.

45 Figure 8 is an elevational view of the back of the oil gauge mechanism showing the casing thereof removed.

Figure 9 is a longitudinal vertical sectional view through the oil connection nipple.

50 Figure 10 is an elevational view of the front of the cam member.

Figure 11 is an elevational view of the back end of the switch mounting.

55 Figure 12 is an elevational view of the side of a key for operating the switch mechanism.

Figure 13 is a wiring diagram of the embodiment of the invention.

Referring in detail to the drawings, the numeral 5 generally designates the embodiment of the invention which comprises a front plate or panel 6 which is arranged to be mounted by bolts or screws passing through the holes 7 to the instrument panel or other support in the operating compartment of the vehicle or control board of the stationary internal combustion engine. 10

The numeral 8 generally designates the front portion of the oil gauge mechanism which is mounted in a suitable opening in the panel 6 and includes the bezel 8 engaging the front part of the casing 9 and holding therein the glass 10. 15

The face of the gauge is designated 11, and the hand 13 is fixed on a pivot 12 which is journaled in the face 11. Secured by one end to the face 11 and by the opposite end to the hand 13 is the small coiled conductive spring 14. The point of 20

grounding of the spring 14 with the face 11 is indicated by the numeral 16. It is to be observed that the spring 14 has no operative function as far as the hand 13 or the shaft 12 is concerned, but is used to make a perfect electrical connection between the hand and the face and hence to ground, which would not exist if reliance for a good electrical connection between these parts was placed alone on the contact between the moving parts. The contact point 19 is fixed on the 25

front end of one arm of a right-angle shaped member 20' mounted on the back of the face and having the said one arm passing forwardly through the face 11. The remaining arm of the member 20' has connected thereto the wire 21. 30

The member 20' is insulated from and mounted to back of the face 11 by screws 18' which enter the front of face 11 and screw into insulated block 19'. 35

The grounded hand 13 has a lateral arm 17 which has a contact point 18 arranged to engage the insulated contact point 19 mounted on the face 11, when the hand 13 is in the extreme left hand position, indicating failure of the lubrication system. The engagement of the contacts 18 and 19 brings into the ignition circuit of the internal combustion engine a grounded resistance sufficient to incapacitate the ignition system and thereby cause stopping and prevent further operation of the engine under certain conditions. 40 45 50

The cylindrical casing of the oil gauge mechanism is generally designated 15 and through a hole in the back thereof shown in Figure 2 the wire 21 is led from the insulated contact point 19 to the binding post 22 of the resistance coil 55

20 which is mounted on the side of the switch mechanism casing as shown in Figure 2. The upper binding post 23 of the resistance coil is connected by the wire 24 to the binding post 25 5 on the switch panel 51. The purpose of the coil 20 is to absorb electric current and thereby eliminate heating of the grounding out circuit contacts 18 and 19 during a period of oiling system failure. The switch mechanism casing is generally designated 50.

10 The face 11 has integral therewith the J-shaped portion comprising the foot part 26 and the vertical part 27 which is substantially parallel to the face. Between the face and the vertical part 27 15 the rock shaft 28 is journaled and is supported in holes in the parts mentioned and has fixed thereto the depending toothed segment or sector 29 which is arranged to be in mesh with the pinion 30 fixed on the oil gauge hand shaft 12. 20 Screws 31 passing through the back of the casting 15 enter the opposite wings or flanges of the oil connection nipple 32 which have the threaded holes 35, 36, so that the said wings are mounted to the inner side of the back of the oil gauge 25 mechanism casing as shown in Figure 7, and the nipple 32 is mounted through a suitable opening in the back of the casing 15 so as to project forwardly therein and engage the back of the face 11 to which it is secured by suitable bolts or 30 screws 37 as shown in Figure 7. The nipple 32 is connected to the oil pipe which is used as the electrical ground.

35 The oil pipe connecting nipple has the threaded portion 38 projecting from the back of the casting for connection with the oil pipe (not shown) and has the bore 40 whose forward end terminates in a tapered converging portion 41 which leads into a small orifice 42 registered with a corresponding hole in the edge or side of the 40 rectangular cross section oil pressure tube 43 which is positioned in the slot 44 in the outward end of the nipple, as shown in Figure 9. The oil pressure tube 43 is arranged as shown in Figure 8 and extends for approximately two-thirds of a 45 complete convolution and has connected to its lower end 45 the spring wire portion 46 which has a vertical arm 47 having a lateral pivot entering a pivot hole 47' in the right hand end of the sector 29 as shown in Figure 8, whereby upon 50 expansion and contraction of the tube 43 in response to the oil pressure in the lubrication system, the sector 29 will be rocked, and correspondingly rock the indicating hand 13.

55 The switch panel 51 of the switch mechanism 50 has a number of contacts arranged thereon for contact by the switch mechanism to be described and these, and their connection with each other and with the ignition system of the internal combustion engine, are as follows:—

60 The contact 52 corresponds to the binding post 25 with which the upper end of the resistance coil 20 is connected, and the contact 53 which is in a horizontal plane with the contact 52 is connected to the distributor casing side of the ignition coil 65 of the engine as shown in Figure 13. It is obvious that when the switch points 52, 53 are bridged by the switch mechanism and the oil gauge contacts 18 and 19 are engaged, during the failure of the lubrication system of the engine, that the 70 resistance coil 20 will be grounded and in circuit with the ignition coil and ground the same to such an extent that the engine will be stopped and will not start again under any circumstances until the grounded resistance has been taken out 75 of the ignition coil circuit. Along the right hand

edge and vertically aligned on the switch panel 51 are in order, downwardly, the headlight dim contact 54, the bright contact 55 and the light tilting switch contacts 56 and 57. To the left of these contacts and in a central portion of the panel 51 and concentric to the boss 52' are the fuse contact points 59, 63 adapted to be engaged to bring the fuse 60 into the light circuits. The battery contact 61 is connected by a connecting strip 62 to the fuse contact 63 above it. The light tilting contacts 56, 57 are similarly connected to the head lamp contacts 64 by the V-shaped strip 65 shown in Figure 2. The cowl or dim lamp contact 66 is similarly connected by a connector 67 to the lamp contact 68. The tail lamp contacts 69, 70 are similarly connected by a connecting strip 71'. The battery contact 61 and the ignition contact 71 are radially spaced from the axis of the switch rotor which corresponds to the position of the boss 52'. It will be observed that the contacts 58, 59 and 69, 70 and 66, 64 are grouped around the boss 52' and are concentric therewith and that the contacts 61 and 71 are arranged radially inwardly of the described contacts and are also concentric to the boss 52'. It will be observed that the contacts 52 and 53 are to be bridged by a safety push button operated circuit closing and opening member to be described, so that the ignition circuit may be closed and normally maintained closed. 30

The safety push button 73 is mounted slidably in a bore in the upper part of the panel 6 and has a slightly reduced portion 74 on which is circumposed the outwardly pressing helical spring 77 which engages the shoulder defined by the outer portion of the safety push button and the back end of the bore in which the button works. The shoulder defined by the inner end of this bore is generally designated 78. A reduced portion 79 of the inner end of this bore has extending therein the reduced rod portion 80 of the safety push button which extends through a horizontal notch in a plate 88 which is fixed to the back of the panel and surrounds the inner end of the reduced portion of the bore as shown in Figure 6. A head 81 is fixed on the reduced portion 80 and is arranged to engage the back face of the plate 88 when the button is in the open position in which it is shown in Figure 6, and this head 81 is cooperated with by the extremity 40 of the arm 85 of the Y-shaped spring pressed 45 latch which is pivoted as indicated at 84 to the back of the plate 88. A lateral rearwardly extending portion on the arm 85 is adapted to move in front of the head 81 as soon as the head 81 has been moved rearwardly in pushing in the button 73, the spring 87 stretched between the point 88 on the plate and the point 83 of the latch acting to swing the arm 85 of the latch in front of the head 81 as soon as the head has been moved rearwardly sufficiently. A rearwardly extending foot 86 on the remaining arm of the Y-shaped latch is arranged for cooperation with the lobe 89 of the cam 90. The purpose of the cam 90 is to push upwardly on the portion 86 of the Y-shaped latch at a certain phase in the operation of the switch mechanism so as to withdraw the portion 85 from in front of the head 81 and thereby permit the spring 77 to push the button 73 outwardly or forwardly. 70

The dielectric disk 103 and the cam 90 are connected to rotate together and the cam has mounted to the forward face thereof the cylindrical stub-shaft 100 which is rotatably mounted in the bore 99 of a thickened portion 91 of the panel 6, 75

and the front of the cam 90 has therein a plurality of depressions or holes 104' with which engages selectively a spring pressed ball detent 104 operatively mounted in the back of the portion 91 as shown in Figure 6. A stop finger 91' on the lower part of the cam 90 is arranged to work in a semi-circular groove 105' formed in the back face of the portion 91 whereby rotation of the cam in both directions is limited. The forward end of the stub-shaft 100 has the normally vertical slot 102 with which the key 95 is arranged to cooperate.

Holes 106' at circumferentially spaced intervals in the cam 90 and in the dielectric disk 103 which is mounted on the back of the cam slidably receive rods 106 which have circumposed thereon springs 107 working between the dielectric disk 103 and the front face of the light contact ring 105. Heads 108 on the back end 20 of the rods 106 retain the contact ring 105 in place and act as contacts to engage the related contacts on the plate 51. These heads 108 are also riveted against the front face of the contact ring 105 so that the contact ring is fixed 25 on the rods 106 and will move the rods forwardly into the holes 106' on the disk 103 as the disk 103 is moved forwardly against the tension of the springs 107.

A spring material segmental ignition contact frame 109 has its top fixedly mounted to the upper part of the disk 103 by a copper rivet 110 and has its lower part slanting rearwardly and downwardly as indicated in Figure 6 and is provided at each side with a rod 109' whose contact head is riveted to the frame 109. The rods 109' are slidable in receiving openings in the disk 103 and have circumposed thereon springs 107 which expand between the back of the disk 103 and the front face of the frame 109. The heads of the rods 109' are arranged to engage the related contacts of the plate 51.

It will be obvious that when the stub-shaft 100 is rotated it will rotate not only the disk 103 and the cam 90 but also the contact ring 105 and the contact frame 109 relative to the stationary contacts which are concentrically grouped around the boss 52'. Projecting rearwardly from the center of the disk 103 is the head of its mounting rivet which is rotatably received in the hole in the front end of the boss 52' which is set in the panel 51 to support the cam rotor.

Means for controllably rotating the cam rotor and selectively contacting different ones of the concentrically grouped stationary contacts comprises the barrel 92 which is mounted in the front part of the bore 99 and contains the helical spring 93. The end of the barrel is provided with a slot 108' and its forward end with an opening suitable to receive the key 95. A washer 98 having a key receiving slot 94, is arranged to have its front face engaged, as the key 95 is inserted, by the shoulder 97 on the key and to be pushed inwardly or rearwardly against the tension of the spring 93, when the key is pushed part way into the key barrel for the purpose of engaging the portion 100' and 99' of the key with the central opening 101', and with the slot 102 in the forward end of the stub-shaft 100 the key will not rotate. But when the key is pushed farther inwardly, the notches 96 of the key will enter the slot 100' in the rear end of the barrel 92, whereat the key will be free to rotate. If the key be rotated while in 75 this position, the cam rotor assembly will be

rotated either to the right or to the left. The key will not operate the cam rotor assembly if the key is not first pushed in all of the way in the manner described. The key locks or stays in when pushed in and turned toward the right 5 or running side but fails to lock in when pushed in and turned toward the parking or left side. The position of the cam while the key is in the "off" position is shown in Figures 5 and 6 wherein the cam 90 is holding the Y-shaped latch 10 out of engagement with the head 81 of the push button rod.

Upon proper manipulation of the key 95 so as to rotate the rotor assembly to the right at least as far as the first step, the engine ignition 15 will be on and the cam will have receded from under portion 86 of the latch and have permitted the spring 87 of the Y-shaped latch to bring the portion 85 of the latch out of a position in engagement with the periphery of the head 81. 20 It is obvious that in this position of the latch the push button 73 may be pushed inwardly or rearwardly against the tension of its spring 77 and that as soon as the head 81 moves rearwardly sufficiently the portion 85 of the latch 25 will drop in front of the head 81 and hold the safety push button in the inward position in which its contact ring 87' will be engaged with and bridge the contacts 52 and 53 and thereby 30 close the resistance circuit. The contact ring 87' is mounted on and is carried by the dielectric disk 72 which slides on the inward end or back end of the rod 80 and is held in the rearward position by the spring 82 which is circumposed on the rod 80 between the dielectric disk 35 72 and the head 81. Bridging of the contacts 52 and 53 by the safety push button contact ring conditions the introduction into the ignition circuit of the resistance coil 20 during engagement of the oil gauge hand contact 18 with the 40 oil gauge contact 19. Therefore, in order to condition operation of the safety ignition circuit grounding contemplated by the invention, it is necessary that the safety push button 73 be 45 pushed in after the engine has been started, after proper operation of the cam rotor by manipulation of the key. When the safety push button 73 is pushed in with the motor running, it will be held in by the latch for the reasons and by the means described. Should the ignition be 50 turned off by operating the key 95 toward the left, the cam will operate the latch so as to release the safety push button 73 outwardly and throw the oil pressure controlled ignition circuit 55 grounding arrangement out of circuit.

Mounted on a pivot 114' fixed on the right hand wall of the casing of the switch mechanism and pivoted thereon is the bright-dim switch operating arm 112 which has the handle 113 60 provided with the hole 114 receiving the pivot 114'. A reduced portion 115 at the rear end of the handle 113 has circumposed thereon the yoke tensioning spring 119. A further reduced flat portion 116 has mounted thereon the yoke composed of the divergent arms 117 and 118 which are insulated from the spring 119 and the handle 113 by the dielectric block 118'. The arms have appropriate contacts for engaging the selected ones of the bright and dim contacts 54, 55 and 56 and 57. The spring 119 keeps the yoke pressed against the selected pair of contacts, such as the contacts 54 and 56 or the contacts 55 and 57, the yoke being slidable upon the reduced flat portion 116. It is obvious that by tilting the 70 handle 113 which projects through the opening 75

120 in the right hand side of the panel 6 that the lights of the vehicle may be changed from bright to dim and vice versa at a touch of a finger providing the switch key 95 has been 5 turned to the bright position on either the running side or the parking side.

In using the device of the invention, the operator places the switch key 95 in the slot 94 and after pressing it inwardly all of the way turns 10 the key either to the left or to the right. If the operator turn the key to the left the only circuits closed as a result are the dim or cowl and the bright tilting light circuits used for parking. If the operator turn the key toward the right 15 instead, the first step closes the ignition circuit and conditions the locking of the safety push button, and the second and third steps maintain the ignition circuit and bring into play also the bright, tilting, and the dim or cowl running light 20 circuits of the vehicle, which bright light circuit may be controlled further by manipulation of the bright-dim switch handle 113 in a manner already indicated.

As soon as the ignition circuit has been closed 25 by turning the key to the right from the off position and the motor has been started, the safety push button 73 is pushed in so as to condition the bringing into the ignition circuit of the grounding resistance coil 20 whenever the hand 30 of the oil gauge should sink under a reduced oil pressure or failure of the lubrication system to the left hand extreme position in which it engages its contact with the contact 19. It is not necessary to push the safety push button 73 in to 35 operate the vehicle, but it is necessary to push in the safety push button 73 at the time indicated if the automatic control of the ignition circuit by the oil pressure of the lubricating system is to be placed in condition for operation.

40 Should a failure of the lubricating system occur while the safety push button 73 is in the pushed in position and the motor should stop, the ignition key 95 may be turned off, whereupon the safety push button 73 will spring outwardly and 45 break the grounded resistance circuit. The ignition key may then be turned to the right and the motor started again, to enable the operator to bring the vehicle to the side of the road or park the same to make repairs or inspection. If 50 upon starting an engine the second time the hand of the oil gauge does not move toward the right, this is an indication of lubricating system failure, and the operator may conduct himself accordingly.

55 Although I have shown and described herein a preferred embodiment of my invention, it is to be definitely understood that I do not desire to limit the application of the invention thereto, and any change or changes may be made in materials and in the structure and arrangement of parts, within the spirit of the invention and the scope of the subjoined claims.

What is claimed is:—

1. In a device of the character described, an 60 oil pressure responsive member, a contact carried thereby, a stationary contact supported to be engaged by said contact in a position of said responsive member corresponding to a lack of oil pressure, said contact being arranged to be disengaged from said stationary contact in another 65 position of said pressure responsive member when the oil pressure is normal, and first switch means having one side connected with one of said contacts and its opposite side to a portion of said 70 ignition system, a second switch having one side 75

connected to a different portion of said ignition system and its remaining side connected to the battery of the ignition system, whereby upon closing of said switches during a closed condition of said contacts said ignition system will be deenergized, said switches including, a rotary member selectively engageable with said contacts, key means for operating said rotary member, a safety push button operable to bridge some of said contacts while others of said contacts are engaged by 10 said rotary member, cam operated means for locking said safety push button in the engaged position, cam means on said rotary member for operating said cam operated means to release said safety push button from engaged position. 15

2. A device for rendering a battery equipped automobile engine ignition system inoperative upon a failure of the oil pressure in the engine, said device comprising a member responsive to the oil pressure and having a contact adapted to 20 be connected to said ignition system, said device further comprising a stationary contact engageable by said contact only when the oil pressure fails, an ignition system grounding resistance connected to said stationary contact and to a 25 part of the ignition system, a safety switch having means to which said resistance is connected, said safety switch being interposed between said ignition system and said resistance, said means being adjustable to condition a connected condition of said resistance with respect to the ignition system, upon engagement of said contact with said stationary contact upon failure of the oil pressure, whereby said resistance is connected to said ignition system so as to render the same 30 inoperative.

3. In combination, a visible safety oil pressure gauge switch, said switch comprising an oil pressure responsive member, a contact carried thereby, a stationary contact supported to be engaged 40 by the first-mentioned contact in a position of said responsive member corresponding to a lack of oil pressure, said first mentioned contact being arranged to be disengaged from said stationary contact in another position of said pressure responsive member when the oil pressure is normal, a grounding resistance coil having one end connected to said stationary contact, a cooperating safety push button switch to one side of which the remaining side of said coil is connected, said 45 safety push button switch having its remaining side arranged for connection to the circuit breaker side of the ignition coil of an ignition system, whereby, with said safety push button switch in closed position, and during a closed condition of 50 said contacts, said ignition system is inoperative. 55

4. A device for rendering an ignition circuit inoperative upon failure of oil pressure in an internal combustion engine, said ignition circuit involving an ignition coil having a circuit breaker terminal, said device comprising a contact movable responsive to the oil pressure and arranged to occupy a first position while the oil pressure is at normal and a second position while the oil pressure is below normal, a stationary contact 65 with which said responsive contact is engageable only in the second position thereof, a resistance arranged to be interposed between one of said contacts and the circuit breaker terminal of the ignition coil, an ignition switch including a cam, 70 a safety push button switch, cam operated latch means on said safety switch operatively engageable by said cam for locking and releasing said push button switch according to whether the ignition switch is in an "off" or an "on" position, 75

said push button switch being interposed between said resistance and the ignition switch, said push button switch conditioning flow of current through said resistance only while said push button switch is in an operated locked position.

5. A device for rendering the ignition coil of an ignition system inoperative upon failure of the oil pressure in an internal combustion engine, said ignition system involving a circuit breaker terminal and a battery, said device comprising an ignition switch interposed between one side of the battery and one side of said ignition coil, a second switch operated by the oil pressure and arranged to occupy an open position while the pressure is at normal and a closed position when the oil pressure falls below normal, said second switch being connected between said circuit breaker terminal and another side of said ignition coil, a third and manually operable safety switch, said safety switch being arranged to be operable closed only while said ignition switch is closed, a resistance interposed between said second switch and said safety switch and arranged to incapacitate said ignition coil only while said ignition switch, said safety switch and said second switch are in their closed positions.

6. A device for deenergizing the ignition coil of a battery equipped ignition system of an internal combustion engine upon failure of the oil pressure in said internal combustion engine, said ignition coil involving a circuit breaker terminal, said device comprising an ignition switch interposed between one side of said battery and the remaining terminal of said ignition coil, a second switch operated by the oil pressure and arranged to occupy an open position while the pressure is at normal and a closed position when the oil pressure falls below normal, said second switch being interposed between said circuit breaker terminal and the remaining side of said battery, a third and manually operable safety switch, said safety switch being arranged to be operable closed only while said ignition switch is closed, a resistance interposed between said second switch and said circuit breaker terminal and arranged to deenergize said ignition coil only while said ignition switch, said safety switch and said second switch are in their closed positions, said ignition switch including latch means engageable with said safety switch while said safety

switch is closed to hold said safety switch closed while said ignition switch is closed, said latch means being disengaged from said safety switch while said safety switch is open.

7. A device for rendering an ignition circuit inoperative upon failure of oil pressure in an internal combustion engine, said ignition circuit involving an ignition coil having a circuit breaker terminal, said device comprising a grounded contact movable responsive to the oil pressure and arranged to occupy a first position while the oil pressure is at normal and a second position while the oil pressure is nil, a stationary contact with which said responsive contact is engageable only in the second position thereof, a resistance arranged to be interposed between one of said contacts and the circuit breaker terminal of the ignition coil, an ignition switch including a cam, a safety push button switch, cam operated latch means on said safety switch operatively engageable by said cam for locking and releasing said push button switch according to whether the ignition switch is in an "off" or an "on" position, said push button switch being interposed between said resistance and said ignition coil, said push button switch conditioning flow of current through said resistance only while said push button switch is in an operated locked position.

8. A device for rendering the ignition coil of an ignition system inoperative upon failure of the oil pressure in an internal combustion engine, said ignition coil involving a circuit breaker terminal, said device comprising an ignition switch connectible in said system, a second grounding switch operated by the oil pressure and arranged to occupy an open position while the pressure is at normal and a closed position when the oil pressure fails, said second switch being interposed between a grounded circular spring, and a third manually operable safety switch, said safety switch being further connected to said circuit breaker terminal of the ignition coil, said safety switch being arranged to be operable to a closed position only while said ignition switch is in a closed position, a resistance interposed between said second switch and said safety switch and arranged to incapacitate said ignition coil only while said ignition switch, said safety switch and said second switch are in their closed positions.

CHARLES JELLIK, Jr. 50
